UNITED STATES PATENT OFFICE

JOHN F. ISBELL, OF ALHAMBRA, CALIFORNIA; CLEMENTINE ISBELL, ADMINISTRATRIX OF SAID JOHN F. ISBELL, DECEASED, ASSIGNOR OF ONE-HALF TO OTTO Q. BECKWITH, OF LOS ANGELES, CALIFORNIA

SCREEN SEPARATOR

Application filed June 19, 1922. Serial No. 569,495.

My invention relates to inclined screen separators for separating and sizing sand, gravel, crushed rock, ores, and similar materials; and particularly embraces new and 5 improved means for vibrating the screen; which greatly increases its capacity; produces highly satisfactory results; and renders it adaptable to either wet or dry screening of an almost infinite variety of materials of all 10 sizes.

The vibrating mechanism is of an oscillatory type—deriving its reciprocatory motion from an unbalanced pulley—which delivers a series of quick, sharp impacts, of high 15 frequency, to the screen; so that its vibratory motion is at right angles to the plane of its surface. While the mechanism is mounted to deliver its impacts on but one side of the screen, its arrangement and operation are 20 such that the impacts are in the nature of blows delivered alternately against the screen from opposite sides; so that, in effect, one blow instantaneously removes the screen from supporting the material and the next successive 25 blow forces it upwardly against it, with such rapidity and intensity that the fines or undersized materials are quickly disposed of. Impacts of this character practically eliminate 30 possibility of the screen becoming clogged by small particles of material lodging in the meshes, which adds greatly to its efficiency and capacity. It is in the delivery of this series of ultra-rapid, sharp and distinct impacts, without deleterious effect upon 35 the mechanism, that the principal success of my invention lies.

A characteristic and highly important accomplishment of my invention is the delivering of four distinct vibratory impacts to the screen on each revolution of the unbalanced pulley; so that the screen may be vibrated at a high frequency rate with a comparatively low belt speed and R. P. M. of the unbalanced pulley. This greatly minimizes wear and tear 40 on the mechanism; and also permits a wide range of adjustment of the intensity of screen vibrations with a correspondingly slight increase or decrease in the R. P. M. of the unbalanced pulley.

45 A further feature of the invention is the

large number of adjustments which may be made to alter the vibratory motion of the screen, from a series of quick, sharp vibrations of high frequency and small amplitude, to a series of heavier vibrations of less frequency, and comparatively large amplitude; and to vary the force of the vibratory impacts. This flexibility renders the mechanism capable of handling a large variety of materials of various sizes, which is highly desirable in 55 the art.

Furthermore, the mechanism is simple in operation; inexpensive to manufacture; and sufficiently strong and durable, with so few 60 wearing parts, that its cost of maintenance 65 will be negligible.

The accompanying drawings illustrate the preferred specific embodiment of my invention, in which—

Fig. 1 is a side elevation of my invention; Fig. 2 is a plan view thereof; Fig. 3 is a longitudinal vertical section, taken as indicated by the line 3—3 of Fig. 2; Fig. 4 is a transverse vertical section, taken as indicated by the line 4—4 on Figs. 2 and 3; Fig. 5 is an enlarged fragmentary sectional view taken as indicated by the line 5—5 of Figs. 1, 2 and 3; Fig. 6 is an enlarged fragmentary sectional view taken as indicated by the line 6—6 of Fig. 2; Fig. 7 is an enlarged side elevation 70 of the unbalanced pulley; and Fig. 8 is a transverse vertical section taken through this pulley as indicated by the line 8—8 of Fig. 7.

75 In the drawings, referring first to Fig. 1, the numeral 10 designates generally a main frame, supported in an inclined position in any suitable manner, as upon corner posts 11 and cross braces 12. It may be set at any desired degree of inclination, say between ten and forty-five degrees, depending upon the character and quantity of material being handled. A distributor or feed chute 13 is supported at the upper side of the frame 10, in any suitable manner; and may be equipped 80 with any of the well known means for effecting an equal distribution of the material across the upper edge of the screen. A discharge chute 14 is provided across the lower edge of the frame 10, into which the tailings or oversized materials from the screen deposit, 85

from whence they may then gravitate into a suitable receptacle 15. A discharge chute 16, into which the fines or undersized materials are deposited through the screen, extends across substantially the entire bottom area of the frame; and the fines may gravitate from the chute 16 into a suitable receptacle, as designated by the numeral 17. The foregoing arrangement is for a single separator or unit; however, any number of units may be mounted one above the other in a zig-zag arrangement for successively screening or separating the finer materials; the oversized materials being discharged from the screens through the chutes 14, and the undersized materials discharged onto the next lower units, as through the chutes 16. Or they may be placed end to end in echelon, so that the oversized materials will be discharged, as through chutes 14, onto the next lower screen, while the undersized materials or fines may be taken off and discharged into suitable receptacles, as through the chutes 16.

The main frame 10 consists of parallel side members, and parallel top and bottom transverse members; the latter preferably being mounted, relative to the former, so they will extend in a vertical plane when the members 18 are mounted in an inclined position, as shown in Fig. 1.

A pair of tubular supporting members 20, upon which the screen and actuating mechanism are mounted, extend transversely across the frame 10; being removably supported in suitable bearing blocks 21 and 22; the latter secured on the top edges of the frame members 18, as by means of bolts or lag-screws 23. The blocks 21 are simple bearing blocks in which the upper supporting member 20 is revolvably mounted; cap screws 24 being provided in their tops to hold this supporting member against rotation therein. The lower bearing blocks 22 are in the nature of pillow blocks, having removable top portions 22^a, secured by cap screws 25; so the screen and its vibrating mechanism may be raised from the position shown in solid lines in Fig. 1 to that shown in dotted lines, with the upper supporting member 20 serving as a fulcrum. This is for the purpose of enabling the replacement or repair of screens, which will be more fully hereinafter explained. When the screen and operating mechanism are raised, as just described, the cap screws 24 are loosened to permit rotation of the member 20 in the bearing blocks 21. It may be here noted that the cap screws 24, and similar screws 26, in the tops 22^a of blocks 22, also serve to hold the supporting members 20 against axial movement.

The vibrating mechanism—generally designated by the numeral 27—is carried upon a pair of frame members 28, which, in turn, are supported upon the tubular supporting mem-

bers 20. The frame members 28 are identical, each consisting of a base or supporting member 29 and a standard 30, which may be formed either integral or separable as desired; being shown here as formed integral. The base members 29 are T-shaped in cross sectional configuration, to provide for lightness and strength of construction, and are carried directly upon the supporting members 20. They are connected at each end to the members 20 by means of integral tubular split bearings 31, through which the members 20 extend; being clamped thereon by means of bolts 32 extending through suitably formed integral lugs 33. In this manner the frame members 28 are mounted axially adjustable upon the members 20.

The standards 30 supported upon the base members 29, extend upwardly in parallel planes, and consist each of a pair of legs 30^a, of substantially the configuration shown in the drawings; being joined intermediate their ends by an integral transverse brace member 34, and at their tops by removable caps 35, secured thereto by means of cap screws 36. Bearing blocks 37 are mounted to slide vertically between the contiguous faces of the legs 30^a, intermediate the transverse braces 34 and the removable caps 35. The blocks 37 have channels cut in their vertical edges, (see Figs. 3 and 4) to form flanges for engaging the opposite edges of the faces 30^b, so they may be moved vertically but held against transverse movement; the faces 30^b being parallel intermediate the transverse braces 34 and the removable caps 35, and finished for this purpose. Blocks 37 are made vertically adjustable by means of screws 38, extending loosely through bores 39 in the caps 35 (Fig. 4), and screw-threadedly engaging bores 40 in the blocks. Lock nuts 41 are provided for rigidly holding the screws and blocks in adjusted position.

A transverse shaft 42 is revolvably journaled in suitable bearings in the bearing blocks 37; and carries a belt pulley 43 rigidly secured thereon, intermediate the juxtaposed standards 30; spacer blocks 44 being likewise rigidly mounted upon the shaft 42, intermediate the bearing blocks 37 and pulley 43, to hold the shaft against axial movement. A belt pulley 45 is likewise rigidly mounted upon the shaft 42, adjacent the outer face of one of the standards 30; and another pulley 46 may also be provided on the outer end of the shaft, to rotate loosely thereon, to which a belt 47 may be shifted, when the vibrator mechanism is to be put out of operation. The belt 47 will be shifted to the pulley 45, to drive the shaft 42 and operate the vibrator mechanism, in the member to be hereinafter described. The belt 47 may be driven from any suitable source of motive power (not shown).

A rocker arm, generally designated by the numeral 48—hereinafter called the “vibrator beam”—is rigidly clamped upon a rock shaft 49 by means of a central split bearing 50; and the rock shaft 49 is, in turn, journaled at each end in suitable bearings 51, formed integral with the base members 29 of the frame members 28. The split bearing 50 is of sufficient length to extend between and abut against the base members 29, to prevent axial movement of the shaft, and also any transverse movement of the vibrator beam relative to the frame members 28. The vibrator beam 48 consists of a pair of coplanar arms 52, extending outwardly from opposite sides of the bearing 50, at right angles to its axis and in alignment with each other, and a pair of parallel arms 53, extending upwardly from the bearing 50 at an angle of substantially 90° with the arms 52.

An unbalanced pulley 54 is rotatably mounted between the arms 53 upon a shaft 55 carried in suitable bearings 56 in their upper ends; and rotation of this pulley gives the vibrator beam its oscillatory motion. The pulley 54 is thus situated directly beneath and in alignment with the pulley 43 and is operatively connected therewith by means of a suitable drive belt 54—A. The pulley 54, illustrated in Figs. 7 and 8, is preferably of the configuration shown, consisting of a hub 57 and a rim or belt surface 58 connected by a central web 59. It is unbalanced by means of eccentric weights 60, removably secured intermediate the hub 57 and rim 58, on either side of the web 59, by means of a bolt 61, extending through the weights and web, as shown in Fig. 8. The weights 60 will preferably be segmental in form, as shown, and as will be later explained they may be provided in different sizes, to adjustably alter the force of vibratory impacts delivered to the screen.

The arms 52, of the vibrator beam 48, terminate at their outer ends in tubular hammers 62; having bores 63, the axes of which extend at substantially right angles to the plane of the arms 52. A pair of bridge members 64, which also serve as braces, extend transversely between the base members 29, intermediate the bearing 50 and the outer ends of the arms 52, as clearly shown in Figs. 3 and 5. These members rest upon the top faces of the members 29, above the arms 52, and have downwardly depending ears 65 coinciding with lugs 66 upon the members 29, through which bolts 67 extend to hold them rigidly in place.

A means for adjustably cushioning the oscillatory force of the arms 52 is provided in the form of studs 68, rigidly mounted upon the arms 52 and extending loosely through apertures 69 in the bridge members 64. Helical springs 70 surround the studs 68 and are confined between the top faces of the bridges 64 and disks 71, secured on their up-

per ends by means of nuts 72. Annular flanges 73 may be formed on the top faces of the bridges 64 to hold the springs 70 against lateral movement.

The details of construction, and the manner of mounting the screen—herein generally designated by the numeral 75—upon the frame 10, forms the subject-matter of a co-pending application for patent, filed on the 19th day of June, 1922, Serial No. 569,496; but in order that its function, in combination with the vibrating mechanism, may be herein clearly understood, I will describe in a general way its construction and operation in so far as it co-operatively functions with the vibrating mechanism hereinbefore described. The screen fabric 76 is carried upon and between a pair of side rails 77, extending parallel with and between the side members 18 of the frame 10. The members 77 are, in turn, suspended from the supporting members 20 by means of hangers 78 rigidly connected to them and hingedly connected at their upper ends—as at 79—to the outer ends of spring bars 80. Both the hangers 78 and the bars 80 are preferably constructed of flat metal, the bars 80 being constructed of spring steel to permit a limited amount of movement of the screen in a direction perpendicular to its surface. The hangers 78, by reason of their hinged connection with the bars 80, will permit a limited amount of lateral swinging movement of the screen in a plane parallel to its surface. The bars 80 are secured to the supporting members 20 by means of clamps 81, which are axially adjustable on the members 20 to vary the points of support of the bars 80 relative to their outer ends. In this manner the portions of the bars 80, intermediate the clamps 81 and the hinged ends 79, may be lengthened or shortened, thereby increasing or decreasing the extent of yielding vertical movement permitted the side rails 77. This means of yieldingly supporting the screen 75 renders it more sensitive and susceptible, throughout its entire surface, to the vibratory impacts of the vibrator beam. The rails 77 are held in spaced relation by means of transverse brace members 82. The screen 76 is secured to the rails 77, and is supported along its upper and lower edges upon reinforcing members 83, which may be constructed of angle-iron of suitable size. In this instance the screen 76 is secured to the angle iron 83 by means of bolts 84, having round heads protruding above the screen so as to present the least possible obstruction to material passing over them. A resilient bar 85 of flat metal is secured at each end to the reinforcing members 83, by means of suitable bolts 86, and extends beneath the screen from its top to bottom edges, directly beneath and in alignment with the vibrator beam 48; this bar also supporting the screen 76 across its longitudinal center.

A pair of studs 87, having heads 87^a, extend upwardly through the bar 85 and screen 75; being retained therein by means of lock nuts 88. The lock nuts 88, together with washers 89, also serve to hold the screen 76 against the bar 85, as clearly illustrated in Figs. 3 and 6. The upper screw-threaded ends of the studs 87 engage in internally screw-threaded bores 90 in tubular adjusting members 91. The 10 studs 87 carrying the adjusting sleeves 91 are situated directly beneath and in axial alignment with bores 63 of the hammer ends 62 of the vibrator beam 48; and studs or cap screws 92, having heads 93 and lower screw-threaded ends 94, extend loosely through the bores 63 in the hammer ends 62 and screw-threadedly engage the upper internally screw-threaded ends of the bores 90 in sleeves 91. The sleeves 91 are split on opposite sides of their 15 opposite ends, as illustrated in Fig. 6, and bolts 95 extend through suitably formed lugs to clamp these opposite ends in adjusted positions upon the studs 87 and 92. With the foregoing described means the extent of 20 oscillatory motion of the vibrator beam 48 may be limited by adjusting the impact surfaces 96 and 97, upon the under faces of the heads 93 of studs 92 and the top ends of the sleeves 91, respectively, relative to the impact 25 surfaces 98 and 99 upon opposite ends of the hammer ends 62 of vibrator beam 48, by first vertically adjusting the sleeves 91 upon studs 87 and then by vertically adjusting studs 92 in the upper ends of sleeves 91. This may 30 be easily accomplished by loosening the clamp bolts 95 and releasing the clamping effect of the split ends of sleeves 91 and then screw threadedly adjusting the studs 87 and 92 in the internally screw threaded bores 90. It 35 may be here noted that the opposite ends of the bores 90 are provided with right-hand threads, or they may be provided with right and left-hand threads for effecting this adjustment. In any event, it is essential that 40 the spaces between the surfaces 96 and 98 and 99 and 97, upon the hammers 62, studs 92 and sleeves 91, be of equal length when the vibrator beam is in its normal central position; or at least that these spaces be equal at 45 both ends of the arms 52. The foregoing construction is preferable, however, it is obvious that other forms may be utilized, as it is only necessary to provide means whereby the arms 52 will deliver vibratory impacts 50 to the screen upon their up and down movements, and in opposite directions upon different portions of the screen.

In operation the screen and vibrator mechanism are in the position, relative to the 55 frame 10, as illustrated in solid lines in Fig. 1, and as shown in Figs. 2, 3 and 4. Power is transmitted to the pulley 45 upon the shaft 42, through the medium of the drive belt 47 (from any suitable source of motive power). The belt pulley 43 being fixed on the shaft 42 rotates the unbalanced pulley 54, through the medium of belt 54—A. The pulley 54, being unbalanced by the attachment of the weights 60, eccentric to its center, and being rotated at a high rate of speed, will 60 cause an oscillatory motion to be transmitted to the vibrator beam 48, as indicated by the arrows in Fig. 3, reciprocatively rocking this whole member upon the shaft 49. This reciprocative or oscillatory motion 65 transmitted to the vibrator beam 48, by rotation of the unbalanced pulley 54, will cause a vertical oscillatory motion, in opposite directions, of the outer ends of the vibrator beam or arms 52, causing the faces 98 and 99 70 of the hammers 62, to very rapidly successively impact against the faces 96 and 97 of the studs 92 and adjustment sleeves 91, thereby transmitting rapid vibratory impacts to the screen 76 through the medium of the studs 87 75 mounted on the bar 85. The vibrations thus transmitted to the screen are very sharp and clear cut, causing the screen to vibrate at a very rapid rate. The screen 76 will be drawn very tight and this will, to some extent affect 80 the sharpness of the vibrations. It is to be noted that the adjustment of the sleeves 91 and the studs 92 relative to the ends 62 of arms 52 will determine the limit of the oscillatory motion of the vibrator beam 48. 85

When the vibrator mechanism is set in motion the material to be separated is fed to the screen through the distributor 13 which may be of any suitable type to properly distribute the material across the top edge of 90 the screen; and the vibration of the screen will cause the undersized materials or fines to pass through the meshes while the oversized or tailings will gravitate downwardly over the surface of the screen and be discharged 95 over the chute 14 into any suitable receptacle, as shown at 15; the undersized material or fines being caught in the chute 16 and deposited in a suitable receptacle 17.

With the present vibrator mechanism the 100 vibrations of the screen are at right angles to the plane of its surface, and being clear cut and sharp, clogging of the meshes of the screen is practically eliminated. This prevention of clogging of the meshes of the 105 screen is also greatly minimized due to the fact that my vibrator mechanism not only delivers an impact to one side of the screen, as, for instance, to move it downwardly away from supporting the material, but it also delivers the equivalent of an impact to the opposite side of the screen which immediately 110 and successively throws it upwardly against the material falling towards it, which adds greatly to the capacity of the screen. These 115 successive impacts delivered as from opposite sides of the screen are also of material importance in increasing its capacity when handling wet material. It is also to be noted that with my device I not only obtain four 120

125

130

times the number of vibrations ordinarily obtained from an impact arm operating at the same speed, but that I also at the same time deliver impacts to the screen as from opposite sides, by the surface 98 engaging the face 96 on stud 92, on one of the arms 52, while the face 99 impacts with the face 97 on sleeve 91 on the opposite arm 52.

A number of adjustments may be made in my mechanism to adapt it to the handling of almost any type of material and for screening through many different sized meshes of screen. This is done by altering the intensity of vibratory motion of the screen, or the limit of oscillatory motion of the vibrator 48 which transmits these vibrations to the screen, causing it to either deliver a series of quick sharp vibrations of high frequency and small amplitude, or a series of heavier vibrations of less frequency and comparatively large amplitude, or to any intermediate vibratory motion.

These adjustments may be accomplished, first, by altering the speed at which the unbalanced pulley 54 is driven; second, by altering the tension of the drive belt 54—A between the pulleys 43 and 54; third, by changing the weights 60 upon the unbalanced pulley 54; fourth, by adjusting the compression of springs 70; and fifth, by adjusting sleeve 91 and studs 92 relative to the ends 62 of arms 52.

The speed of the drive belt 47, of course, may be altered in any suitable way, common to the increase or decrease of speed of such belts. The tension of the drive belt 54—A is altered by vertically adjusting the bearing blocks 37 upon the standards 30, relative to the unbalanced pulley 54, through the medium of the screws 38. Tightening this belt will of course cushion and limit to a certain extent, the oscillatory motion of arms 52 and 53 and unbalanced pulley 54, (in the direction indicated by the arrows in Fig. 3). This adjustment has more of a cushioning effect upon the vibrator beam 48 than anything else. The extent to which the pulley 54 is unbalanced may be altered by changing the weights 60 upon it, either increasing or decreasing their size and weight, which will alter the extent to which rotation of this pulley will transmit oscillatory motion to the arms 52 and 53 and vibrator beam 48 and will alter the force of its impacts in proportion to the extent of their movements. The adjustment of compression of springs 70 is effected through the medium of the nuts 72 upon the upper end of the studs 68; and this adjustment also has a tendency to produce a cushioning effect upon the oscillatory motion of the vibrator beam 48; but principally their function is to balance up the impacting force of the arms 52 and compensate for slight inequalities in adjustments of studs 87 and 97 and sleeves 91. Both the springs 70 and tension of belt 56,

will have this cushioning effect and will more or less limit the degree of force with which the hammer ends 62, upon the arms 52, will impact against the sleeves 91 and heads 93 of studs 92. The extent of oscillatory motion of the vibrator beam 48 is, of course, adjusted through the medium of sleeves 91 and studs 92, relative to the hammers 62, as hereinbefore described. It is obvious that any of these adjustments may be made individually to effect the vibratory motion of the screen 76, or they may all be made so as to have their cumulative effects to adapt the screen to materials of different sizes and character.

Thus regulation of the speed of rotation of the unbalanced pulley will regulate the number of vibratory impacts delivered to the screen per minute; while regulation of the distance of throw of the arms 52, with or without alteration of the weights upon the unbalanced pulley, will alter the force of the impacts. Changing of the weights upon the unbalanced pulley may also alter the force of the impacts without altering the distance of throw of the arms 52, and without altering the vibratory frequency of the impacts.

The screen 75 being yieldingly suspended and the vibrations transmitted to it through the vibrating mechanism 27, as hereinbefore described, the vibrations will be transmitted throughout the entire surface of the screen so that the material adjacent the side rails 77 will be just as efficiently screened and handled as that at the center of the screen. This is due to the resilient or yielding suspension of the screen.

Owing to my particular manner of producing the oscillatory motion of the vibrator beam 48, and the fact that these motions are only limited by the impact surfaces on the hammers 62 engaging the impact surfaces on the sleeves 91 and studs 92, excessive wear and tear upon and racking of the mechanism is avoided. The impacts of the hammers with the sleeves 91 and studs 92 are the only positive and fixed stops to the motion of the vibrator beam; all the other means being cushioning stops to its movements. This produces an extremely durable mechanism, and conduces to low cost of maintenance.

While I have shown and described a preferred specific embodiment of my invention, and the manner in which it may and will ordinarily be used, I nevertheless reserve the right to make such changes or modification in structure, and such rearrangements of parts as will properly come within the scope of the appended claims. In this connection it may be mentioned that any number of the vibrator units, comprising the frame members 28, with the drive pulleys and vibrator beam mounted thereon, may be mounted upon supports 20, to transmit vibrations to a single screen. This may be done merely by adjustably mounting these mechanisms at the desired points over

the screen upon the supports 20. In this manner one large screen may be vibrated by a number of vibratory units, avoiding the necessity of constructing a number of small screens. Also, while I have merely shown one screen 76, it is obvious that I may use several superposed screens, as in the case of scalper screens with successively finer screens beneath them, so that a number of grades of material may be separated in a single device.

Furthermore, the vibrating mechanism need not, in all cases have direct connection with the screen, as its vibratory impacts may, for some uses, be transmitted to the screen frame or other support; or it may be used in connection with a device for separating materials, such as a concentrator table, where no screen is used. Also, in its broader aspects, the invention need not be limited to a vibratory beam pivoted at its center, as this element may be in the form of a bell crank having only one arm 52. By this means, the primary principle of my invention, including the feature of the transmission of the vibrator impacts to the screen, transversely to its screen surface and alternately in opposite directions, may be effectively carried out.

I claim:

1. In a device for separating materials, the combination of a suspended screen, and means to vibrate said screen by delivering vibratory impacts to the suspended portion of the screen, alternately in opposite directions, transverse to the plane of its surface.

2. In a device for separating materials, the combination of a suspended screen, means to vibrate said screen by delivering vibratory impacts to the suspended portion of the screen, alternately in opposite directions, transverse to the plane of its surface, and means to yieldingly support said screen, said means being yielding in the direction of the force of the vibratory impacts.

3. In a device for separating materials, the combination of a suspended screen, means to vibrate said screen, said means comprising a rocker arm adapted to deliver vibratory impacts to the suspended portion of the screen, alternately in opposite directions, transverse to the plane of its surface.

4. In a device for separating materials, the combination of a suspended screen, means to vibrate said screen, said means comprising a rocker arm adapted to deliver vibratory impacts to the suspended portion of the screen, alternately in opposite directions, transverse to the plane of its surface, means to yieldingly support said screen, said means being yielding in the direction of force of the vibratory impacts, and means to vary the extent of its yielding movement.

5. In a device for separating materials, the combination of a screen secured around its marginal edges to a supporting frame, and

means to vibrate said screen, said means comprising a rocker arm adapted to deliver vibratory impacts to the central unsupported area of the screen, alternately in opposite directions transverse to the plane of its surface, and means to oscillate said rocker arm.

6. In a device for separating materials, the combination of a screen, means to vibrate said screen, said means comprising a rocker arm adapted to deliver vibratory impacts to the screen, alternately in opposite directions transverse to the plane of its surface, an unbalanced pulley carried by said rocker arm to oscillate it, a drive pulley mounted adjacent the unbalanced pulley, a belt connection between said pulleys, said drive pulley being adjustable towards and away from the unbalanced pulley to vary the extent of oscillatory motion of the rocker arm.

7. In a device for separating materials, the combination of a screen, a frame mounted adjacent the screen, a rocker arm pivotally mounted on the frame, means to oscillate the rocker arm, means carried by the screen adapted to be engaged by the rocker arm whereby said arm delivers vibratory impacts to the screen alternately in opposite directions transverse to the plane of its surface, and means in connection with the arm and frame to adjustably vary the force of the vibratory impacts of the arm.

8. In a device for separating materials, the combination of a screen, a rocker arm pivotally mounted adjacent the screen, means to oscillate said arm, means carried by the screen adapted to be engaged by the rocker arm whereby said arm delivers vibratory impacts to the screen alternately in opposite directions transverse to the plane of its surface, said means being adjustable to vary the extent of oscillatory movement of the rocker arm.

9. In a device for separating materials, the combination of a main frame, a screen yieldingly supported on said frame and yielding in a direction transverse to the plane of its surface, a second frame carried by said main frame, a rocker arm pivotally mounted central of its ends on said second frame, an unbalanced pulley carried by said rocker arm to oscillate it, a drive pulley carried by the second frame adjacent the unbalanced pulley, a belt connection between said pulleys, the drive pulley being adjustable towards and away from the unbalanced pulley to vary the extent of oscillatory motion of the rocker arm, adjustable cushioning means in connection with the arm and second frame to vary the force of oscillatory motion of the arm, impact members carried by the screen positioned and arranged to be impinged by the ends of the rocker arm to deliver vibratory impacts to the screen in opposite direction transverse to the plane of its surface, said impact members being adjustable to vary the

- extent of oscillatory motion of the rocker arm.
10. In a device for separating materials the combination of a material supporting member, means to vibrate said supporting member, said vibrating means being adapted to deliver vibratory impacts to said member in opposite directions transverse to the plane of its material supporting surface, and adjustable means to yieldingly support said material supporting member, said means being yielding in a direction substantially parallel to the direction of force of the vibratory impacts.
11. In a device for separating materials the combination of a material supporting member, means to vibrate said supporting member, said vibrating means being adapted to deliver vibratory impacts to said member in opposite directions transverse to the plane of its material supporting surface, said vibrating means being adjustable to vary the force and frequency of its impacts, and means to yieldingly support said material supporting member, said means being yielding in a direction substantially parallel to the direction of force of the vibratory impacts.
12. In a device for separating materials the combination of a material supporting member having a material supporting surface, means to vibrate said member, said means being adapted to deliver vibratory impacts to said member in a direction transverse to the plane of its material supporting surface and being adjustable to vary the force and frequency of its impacts, and means to yieldingly support said material supporting member, said means being yielding in a direction substantially parallel to the direction of force of the vibratory impacts.
13. In a device for separating materials the combination of a material supporting member having a material supporting surface, means to vibrate said member adapted to deliver vibratory impacts in a direction transverse to the plane of its material supporting surface, and means to yieldingly support said material supporting member, said means being yielding in a direction substantially parallel to the direction of force of the vibratory impacts and adjustable to vary the extent of its yielding movement.
14. In a device for separating materials the combination of a material supporting member having a material supporting surface, means to vibrate said member by delivering vibratory impacts thereto in opposite directions transverse to the plane of its material supporting surface, and being adjustable to vary the force and frequency of its impacts, and means to yieldingly support said material supporting member, said means being yielding in a direction substantially parallel to the direction of force of the vibratory impacts and adjustable to vary the extent of its yielding movement.

15. In a device for separating materials the combination of a material supporting member having a material supporting surface, means to vibrate said member by delivering vibratory impacts thereto alternately in opposite directions transverse to the plane of its material supporting surface, and being adjustable to vary the force and frequency of its impacts, and means to yieldingly support said material supporting member, said means being yielding in a direction substantially parallel to the direction of force of the vibratory impacts and adjustable to vary the extent of its yielding movement.
16. In a device for separating materials, the combination of a material supporting member having a material supporting surface, means to vibrate said member, said means comprising a rocker arm adapted to deliver vibratory impacts to said member in a direction transverse to the plane of its material supporting surface, means to oscillate said rocker arm, and means to yieldingly support said material supporting member, said means being yielding in a direction substantially parallel to the direction of force of the vibratory impacts and adjustable to vary the extent of its yielding movement.
17. In a device for separating materials, the combination of a material supporting member having a material supporting surface, means to vibrate said member, said means comprising a rocker arm adapted to deliver vibratory impacts to said member in a direction transverse to the plane of its material supporting surface, means to adjust the force and frequency of its impacts, means to oscillate said rocker arm, and means to yieldingly support said material supporting member, said means being yielding in a direction substantially parallel to the direction of force of the vibratory impacts and adjustable to vary the extent of its yielding movement.
18. In a device for separating materials, the combination of a material supporting member having a material supporting surface, means to vibrate said member, said means comprising a rocker arm adapted to deliver vibratory impacts to said member in opposite directions transverse to the plane of its material supporting surface, and means to oscillate said rocker arm.
19. In a device for separating materials, the combination of a material supporting member having a material supporting surface, means to vibrate said member, said means comprising a rocker arm adapted to deliver vibratory impacts to said member in opposite directions transverse to the plane of its material supporting surface, means to adjust the force and frequency of its impacts, and means to oscillate said rocker arm.
20. In a device for separating materials the combination of a material supporting

- member having a material supporting surface, means to yieldingly support said material supporting member, means to vibrate said member, said means comprising a rocker arm adapted to deliver vibratory impacts to said member in opposite directions transverse to the plane of its material supporting surface, means to adjust the force and frequency of its impacts, and means to oscillate said rocker arm.
21. In a device for separating materials the combination of a material supporting member having a material supporting surface, means to vibrate said member, said means comprising a rocker arm adapted to deliver vibratory impacts to said member in opposite directions transverse to the plane of its material supporting surface, means to oscillate said rocker arm, and means to yieldingly support said material supporting member, said means being yielding in a direction substantially parallel to the direction of force of the vibratory impacts and adjustable to vary the extent of its yielding movement.
22. In a device for separating materials the combination of a material supporting member having a material supporting surface, means to vibrate said member, said means comprising a rocker arm adapted to deliver vibratory impacts to said member in opposite directions transverse to the plane of its material supporting surface, means to adjust the force and frequency of its impacts, means to oscillate said rocker arm, and means to yieldingly support said material supporting member, said means being yielding in a direction substantially parallel to the direction of force of the vibratory impacts and adjustable to vary the extent of its yielding movement.
23. In a device for separating materials the combination of a material supporting member having a material supporting surface, means to vibrate said member, said means comprising a rocker arm, impact members in connection with said material supporting member, means to oscillate said rocker arm, said rocker arm being adapted to impinge against said impact members during its oscillatory movement to deliver vibratory impacts to the supporting member alternately in opposite directions transverse to the plane of its material supporting surface.
24. In a device for separating materials the combination of a material supporting member having a material supporting surface, means for vibrating said member, said means comprising a rocker arm, means to oscillate said rocker arm, impact members carried by said material supporting member, the ends of said rocker arm being adapted to impinge against the impact members during its oscillatory movement to deliver vibratory impacts thereto simultaneously in opposite directions at its opposite ends and alternately in opposite directions at each end.
25. In a device for separating materials the combination of a material supporting member having a material supporting surface, means for vibrating said member, said means comprising a rocker arm, means to oscillate said rocker arm, impact members carried by said material-supporting member, the ends of said rocker arm being adapted to impinge against the impact members during its oscillatory movement to deliver vibratory impacts thereto simultaneously in opposite directions at its opposite ends and alternately in opposite directions at each end, the direction of force of said impacts being transverse to the plane of the material supporting surface.
26. In a device for separating materials the combination of a material supporting member having a material supporting surface, means for vibrating said member, said means comprising a rocker arm, means to oscillate said rocker arm, impact members carried by said material supporting member, the ends of said rocker arm being adapted to impinge against the impact members during its oscillatory movement to deliver vibratory impacts thereto simultaneously in opposite directions at its opposite ends and alternately in opposite directions at each end, and means to vary the force and frequency of said impacts.
27. In a device for separating materials the combination of a material supporting member having a material supporting surface, means for yieldingly supporting said member, means for vibrating said member, said means comprising a rocker arm, means to oscillate said rocker arm, impact members carried by said material supporting member, the ends of said rocker arm being adapted to impinge against the impact members during its oscillatory movement to deliver vibratory impacts thereto simultaneously in opposite directions at its opposite ends and alternately in opposite directions at each end, the direction of force of said impacts being transverse to the plane of the material supporting surface.
28. In a device for separating materials the combination of a material supporting member having a material supporting surface, adjustable means for yieldingly supporting said member, means for vibrating said member, said means comprising a rocker arm, means to oscillate said rocker arm, impact members carried by said material supporting member, the ends of said rocker arm being adapted to impinge against the impact members during its oscillatory movement to deliver vibratory impacts thereto simultaneously in opposite directions at its opposite ends and alternately in opposite directions at each end, and means to vary the force and frequency of said impacts.

29. In a device for separating materials the combination of a screen, adjustable means for yieldingly supporting said screen, a rocker arm pivotally mounted central of its ends, an unbalanced pulley carried by said 5 rocker arm to oscillate it, impact members carried by the screen positioned and arranged to be impinged by the ends of the rocker arm to transmit vibratory impacts to the screen in opposite directions transverse to the plane 10 of its surface, said impact members being adjustable to vary the extent of oscillatory movement of the rocker arm, and means in connection with said rocker arm and unbalanced pulley to vary the force and frequency 15 of its vibratory impacts.

30. In a device for separating materials, the combination of a relatively immovable member having a material supporting surface, means to vibrate said surface comprising a relatively movable member arranged to deliver intermittent vibratory impacts thereto, alternately in opposite directions and transverse to the plane of said surface.

25 31. In a device for separating materials, the combination of a suspended screen, and means to vibrate said screen by delivering vibratory impacts to the suspended portion of the screen, alternately in opposite directions 30 and transverse to the plane of its surface, said impacts being delivered to effect the initial vibratory movement of the screen in the direction of the impacting force applied.

32. In a device for separating materials, 35 the combination of a relatively immovable member having a vibratory material supporting surface, means to vibrate said surface comprising a relatively movable member arranged to deliver intermittent vibratory impacts thereto, alternately in opposite directions and transverse to the plane of said surface, said impacts being delivered to effect the initial vibratory movement of the screen in the direction of the impacting force applied.

40 45 In witness that I claim the foregoing I have hereunto subscribed my name this 2nd day of June, 1922.

JOHN F. ISBELL.

CERTIFICATE OF CORRECTION.

Patent No. 1,744,899.

Granted January 28, 1930, to

JOHN F. ISBELL.

It is hereby certified that the above numbered patent was erroneously issued to "Clementine Isbell, Administratrix of the estate of John F. Isbell, deceased, assignor of one-half to Otto Q. Beckwith, of Los Angeles, California", whereas said patent should have been issued to "Claudia I. Silvey, administratrix of John F. Isbell, deceased, and Otto Q. Beckworth, of Los Angeles, California", said Beckworth being assignee of one-half interest in said invention, as shown by the records of assignments in this office; and that the said Letters Patent should be read with this correction therein that the same may conform to the record of the case in the Patent Office.

Signed and sealed this 11th day of March, A. D. 1930.

(Seal)

**M. J. Moore,
Acting Commissioner of Patents.**
